(57) **CLAIM**

The ornamental design for a flow cell for a particle-detecting optical monitor, as shown and described.

DESCRIPTION

FIG. 1 is a perspective view of a flow cell for a particle-detecting optical monitor showing our new design;

FIG. 2 is a front view of the flow cell for a particle-detecting optical monitor of FIG. 1;

FIG. 3 is a rear view of the flow cell for a particle-detecting optical monitor of FIG. 1;

FIG. 4 is a left side view of the flow cell for a particle-detecting optical monitor of FIG. 1;

FIG. 5 is a right side view of the flow cell for a particle-detecting optical monitor of FIG. 1;

FIG. 6 is a top plan view of the flow cell for a particle-detecting optical monitor of FIG. 1;

FIG. 7 is a bottom plan view of the flow cell for a particle-detecting optical monitor of FIG. 1;

FIG. 8 is a cross-sectional view taken along line 8-8 of FIG. 6; and,

FIG. 9 is a perspective view of the flow cell for a particle-detecting optical monitor of FIG. 1 shown disposed between a pair of supply elements.

The portion(s) of the supply elements and the cross-sectioned material shown in broken lines are for environmental purposes only and do not form part of the claimed design.
